ORNAMENTAL METAL RAILING, FENCE, ETC.

Frederick S. Schrage, Rock Island, Ill., assignor to Harley E. Bergren, Bettendorf, and Lloyd J. Adkins, Washington, Iowa

Application November 10, 1955, Serial No. 546,044

17 Claims. (Cl. 256—21)

This invention relates to an ornamental railing, fence, etc., primarily for exterior stairs, and more particularly to such structure of the pre-fabricated, knock-down or "do it yourself" type.

The invention features simplicity, economy, ease of assembly and adaptability to installation in a wide variety of stair or step situations, which features stress primarily ready adjustability of the structure with virtually no cutting and no on-the-job welding or other tool requirements beyond the range of the usual home-equipped work bench. A significant and one of the most important objects of the invention is the use of arcuate corner-connecting elements and intermediate elements, each preferably in the form of a ring and/or a part-ring, parts of the circumference of each of which are slotted for cooperation with neighboring elements, posts and rails by means of simple fasteners used in the slots and in apertures designed for register with the slots; while these are loose the assembled structure may be adjusted to fit a selected set of stairs for example. After the proper slope or angle has been achieved, the fasteners are tightened and the entire structure becomes unitary and rigid.

It is another object of the invention to utilize readily adaptable or so-called standard lengths or lengths which may be used in easy-to-handle multiples, and which may be readily trimmed on the job to achieve necessary joints by a common hack saw. Because of the provision for adjustment as among the rings, part-rings, posts and rails, a minimum of skill is required for installation, primarily because the various components are properly coordinated and the overall design is therefore extremely flexible.

The foregoing and other important objects and desirable features of the invention will become apparent as the description proceeds in connection with the drawing, the several figures of which are described immediately below.

Figure 1 is an elevation of one form of assembled railing as used on an exterior porch or stoop and stairs.

Figure 2 is an enlarged section on the line 2—2 of Figure 1.

Figure 3 is a longitudinal section as if seen on the line 3—3 of Figure 2.

Figure 4 is a perspective of one of the rings.

Figure 5 is a plan view of one form of corner post with portions shown in broken lines.

Figure 6 is a partial elevation of the corner post of Figure 5.

The numeral 10 in Figure 1 represents an exterior wall of a residence or other building; 11 indicates a stoop; and 12 designates steps from the stoop. The assembled railing structure includes a horizontal section H on the stoop and a sloping section S along the steps. Each section is made up of the same types of basic components; namely, post members 13, rail members 14^a, 14^b, 14^c and 14^d, individual rings 15, and rings 16 connected by spokes 17. These, together with fastener means, preferably bolts 18 and nuts 19, complete the ordinary assembly. The nuts 19 are preferably of the flexible-metal

2

"speed" type and readily adapt themselves to the curvature of the rings. The bolts have relatively large, slotted heads to cover joints, etc. and are readily handled with a conventional screw driver.

5 As best shown in Figure 2, the rails or rail members are channels, the internal width of which is sufficient to closely accept a portion of each ring 15 and 16, as the case may be. The parts are preferably of metal; although, the material, currently the best for the purpose, is not of limiting significance. The ring and spoke assemblies are each preferably of one-piece design, the rings 16 being formed on the ends of a spoke and welded as at 20 to form a circle. The rails are preferably assembled with their open sides down, which improves the appearance of 15 the structure and avoids the collection of water and debris that would occur if assembled open side up. The spokes 17 may have an ornamental twist therein, the presence or absence of which does not detract from the novelty disclosed and claimed herein.

20 Here as in the claims the expressions front, rear, top, bottom, etc. are used in the interests of convenience and should not be taken as limiting the invention.

The posts 13, with a possible exception to be noted below, are identical and each may be set into the stoop and steps, if concrete, in any well known manner; or, they may have flanged bases as is not unconventional. In any event, they rise from their respective positions to free terminal upper ends. Each post at its upper end has a corner-connecting or brace element in the form of a C-shaped or part ring element 21, the open side of which is down so as to receive and embrace the upper end of the post from above. The free or terminal ends of the C that afford the post-receiving gap are rigidly secured, preferably by welding at 22, to the front and rear faces of 30 the post. The remaining circumferential extent or closed side of each C-shaped element affords arcuate outer surface portions arrangeable with selected rails 14^a, 14^b, 14^c and 14^d and/or rings 15 and 16, as will presently appear. The diameters of the rings 15 and 16 and the part-rings 25 or C-shaped elements are uniform, and all have the same characteristic of presenting their circumferences or portions thereof as arcuate outer mounting surfaces. The primary consideration here is that the rings and C-shaped elements are tangent at one or more places to their neighboring components.

Each post has at its lower end portion front and rear part-rings 23 and these, plus the C-shaped upper element 21, afford the basic connectors from which the assembly 35 proceeds. The exception referred to above may occur in connection with the post 13 that is proximate to the building exterior 10, in which case the rear part ring 23 may be removed to permit installation of that post flush with the wall as shown. Or the connection may be made directly via a ring 15 or 16 or a special post may be provided.

40 This connection may, however, be varied according to individual preference.

45 In the assembly of the structure, after the three posts 13 have been arranged, a certain difference in level will 50 of course exist between the post on the lowest step 12 and the first post on the stoop 11. A line drawn from one to the other will then lie at a certain angle to the horizontal, which will also be the angle or slope of the top and bottom rails 14^a and 14^b. The rails between the 55 front and rear posts on the stoop will of course be level or horizontal. The angle of the rails in the step section S will vary among different jobs but it is a feature of this invention that such variations are no obstacle to universal applicability of the structure. This results from the 60 changes in angle permitted with no sacrifice in rigidity and without bending or other deformation and this in turn stems from the novel construction of the arcuate 65

70

elements comprising the rings and part-rings 15, 16, 21 and 23, the details of which will appear below.

The C-shaped element or part ring 21 has preferably three circumferential slots therein, one at 24 in the top or upper portion thereof; another at 25 in its front portion and another at 26 in its rear portion (Figure 3). Reference here to "front," "rear" etc. means as seen by a person ascending the stairs. The lower part-rings 23 are slotted at front and rear portions as is suggested in Figure 1 and as will be apparent from its substantial duplication, at least in essentials, of the part-ring 21. It will be noted that each slot 24, 25, 26 has a substantial arcuate extent, here forty-five degrees; although, the extent may obviously be varied without departure from the present invention. Also, the slot 24 is in an upper front portion of the arc, the slot 25 is in a front lower portion, and the slot 26 is in a rear lower portion. Stated otherwise, there is a slot in each of three of the four quadrants of the C, the slots 24, 25 and 26 appearing respectively in the second, third and fourth quadrants. In the part-rings 23, and considering these as part of the same circle, which they are, the slots are in the third and fourth quadrants.

In the case of the rings 15, each has three slots 27, 28 and 29, respectively, in the first, second and fourth quadrants. The same is true of three slots 30, 31 and 32 in each ring 16.

A feature of the post 13 is that the C is spaced ahead, above and behind the front, top and rear, respectively, of the post, leaving room for the nuts 19 (Figure 3). The post is preferably tubular and one wall thereof is extended at 33 and welded or otherwise united to the upper arc of the C to increase the strength thereof.

In the corner post shown at 34 in Figures 5 and 6, there is a C-shaped element 35 like that at 21 and in addition there is a part-ring 36 like one of the part-rings 23. The C is slotted at 37, 38 and 39 to correspond to the slots 24, 25 and 26 of the C-shaped element 21.

The part-ring 36 is slotted only at 40 and walls of the tubular post 34 are extended upwardly at 41 and 42 for welding respectively to the elements 35 and 36, which are at right angles to each other. Hence, a pair of rails 14^a and 14^b (shown in broken lines for clarity) assembled at 35-36 will be mitered at 14^a and a single fastener 45^a in the slot 37 will accommodate and hold the mating ends of the rails. This is sufficient when it is considered that each rail is additionally secured to and by the next adjacent ring 15, which is also true of the joint at the bottom of the post 34 except that, since the right-angle-related post part-rings (not shown, but like 23 and 36) do not intersect, the bottom rails will be supported by rings such as 15. It should be understood that the portion of the ring to the right of the post 34 is not used in the corner assembly.

After the posts 13 have been set up, one method is to complete the section H and then start the section S from the lowermost or front post 13, setting the rails 14^a and 14^b temporarily in position to determine lengths and also the angle of the cut at the joint between the top rail and the top rail of the section H, as at 43, as well as the angle of the joints at 44 with the front and common posts. The top rail 14^c in the section H is secured by fasteners 18 and 19 to the C-shaped elements 21 of the H section posts 13 via the slots 24 and suitable registering apertures 45 in the rails. There are a plurality of uniformly spaced such apertures in the rails, thus eliminating the need for drilling, except on rare occasions. Because of the spacing of the apertures 45 and the relation thereof to the uniformly-diametered rings 15 and 16 and part-rings 21 and 23, the use of these components in multiples naturally follows. In the arrangement shown, the individual rings 15 are alternated with the joined rings 16, it being understood that each spoke constitutes one form of means for interconnecting its rings 16. This is a typical assembly but is by no 75

means the only one. The upper series of rings 15, 16 is alined along the underside of the top rail 14^c, the rings being in tangentially consecutive order (each tangent to its neighbor) and each ring is further tangent to the rail. The end rings in each series are respectively tangent to the arcuate elements afforded by the elements 21 on the posts. This is true as to both sections H and S, for, regardless of the slope or angle of the rails in the section S, the slots in the rings and part-rings are equal to the task of accommodation as long as the fasteners 18, 19 are left loose enough for adjustment which, when finally determined, is secured by tightening of the fasteners. Of course, the slots serve a further function other than permitting adjustment in a job undergoing installation: they enable a single typical assembly to be used for a variety of jobs. The angle of the rails in the section S determines the length of the rails and accordingly the nature of the joint at 43, but this and the joints between the lower rail 14^d of the section S and the posts 13, as at 44, are the only places where cutting or fitting is required. The front of the top rail 14 may be trimmed off at 46 if desired.

The tangential relationship among the rings, part-rings and rails, as described above, follows also for the lower series in the sections H and S; and is also characteristic when the corner post of Figures 5 and 6 (or any equivalent) is used. The same is true when the section H, for example, is increased in length, which, as is equally true of the section S, is accomplished by repeating the sections. Flush or straight-across joints will be achieved at each post that is common to neighboring sections except where the angle between the sections changes, as at 43.

When the fasteners are tightened the utmost in rigidity is achieved. As previously stated, the width of each ring is such that an arcuate portion thereof tightly fits the channel-section of the top rail. Each intermediate ring 15, 16 has three points of connection, two with neighboring rings and one with a rail. The front and rear halves of the C-shaped element 21 have rigid connections to the post 13 (welded at 22) and each half has a connection to the end ring 15 in a series, plus a connection to a rail. In each case the theory of triangular rigidity is achieved. The arrangement is such that when the components in the section S, or a similar section, are assembled loosely, without the rails 14, the entire section may be adjusted from a right rectangle to a parallelogram, within the limits of the ring and part-ring slots, since these components "roll" about each other and the fasteners slide angularly in the slots. If the spokes and posts are kept plumb, the rings will line up according to the angle required by the steps, after which the fasteners may be tightened and the rails 14^a and 14^b cut and installed.

The foregoing characteristics are only a few that go together to make this design practicable, economical and simple. Other features not categorically enumerated herein will undoubtedly occur to those versed in the art, as will various modifications of the preferred embodiment disclosed, all of which may be achieved without departure from the spirit and scope of the invention.

What is claimed is:

1. A railing assembly, comprising: front and rear spaced apart posts, each having a terminal upper end and front and rear upright faces; front and rear rail-mounting elements respectively on said front and rear posts, each element being a part ring having circumferentially spaced apart lower terminal ends affording a gap through which the upper end of the associated post extends diametrically as respects said part ring, the terminal ends of each part ring being rigidly secured respectively to the front and rear faces of the associated post with said part ring curving upwardly ahead of, rearwardly over and downwardly

behind the upper end of said post to respectively provide integral front, top and rear portions, each part ring having a continuous circumferential slot in part in its forward portion and in part in its top portion; a top rail extending between the posts and having front and rear ends respectively supported on the part rings and respectively tangent thereto at the portions thereof including said slots, each end of the rail having an aperture therein in register with the respective slot; and a pair of releasable fastener means, one passed through each slot and its registering aperture, said fastener means being releasable to slide in their respective slots to enable adjustment of the top rail and posts circumferentially about the part rings, and said fastener means being securable to fix said adjustment.

2. The invention defined in claim 1, in which: the radius of each part ring is sufficiently larger than the fore-and-aft dimension of the associated post as to provide a space for accommodating a fastener means between the front face of said post and the inner surface of the slotted upper forward portion of said part ring.

3. The invention defined in claim 1, in which: the rear part ring has a second circumferential slot in the top and rear portions thereof; a second top rail extends rearwardly from said rear part ring and has a front end supported on said rear part ring and tangent thereto at said second slot, said front end having an aperture in register with said second slot; and fastener means is releasably received in the last-mentioned slot and aperture for adjustably securing the second top rail to said rear part ring.

4. The invention defined in claim 1, including: an upper series of rings alined below and individually tangent to the undersurface of the top rail and in tangentially consecutive order as respects each other, the front and rear rings of said series being tangent respectively to the rear portion of the front part ring and the front portion of the rear part ring, said rings respectively having circumferential slots at the points of tangency respectively with the rail and part rings and the rail and part rings respectively having apertures at said points of tangency and in register with the respective slots; and a plurality of fastener means releasably received respectively by the registered slots and apertures for selective release and securement to respectively accommodate and fix adjustment between the rail and posts.

5. The invention defined in claim 4, including: a bottom rail extending between lower portions of the posts and having front and rear ends respectively proximate to said lower post portions; front and rear lower part-ring elements secured respectively to the rear of the front post and to the front of the rear post above the bottom rail, said lower front part-ring element lying substantially semi-circularly behind the lower portion rear face of the front post to present an arcuate lower rear portion tangent to the front end of the bottom rail and provided with a circumferential slot including the point of tangency, said lower rear part-ring element lying substantially semi-circularly ahead of the lower portion front face of the rear post to present a lower front portion tangent to the rear end of the bottom rail and provided with a circumferential slot including that point of tangency, said front and rear ends of the bottom rail having apertures respectively in register with the slots in the lower part-ring elements; and front and rear lower fastener means respectively received in the slots and apertures for selective release and securement along with the previously mentioned fastener means to respectively secure and fix adjustment of the rails and posts.

6. The invention defined in claim 5, including: a lower series of rings alined above and individually tangent to the top surface of the bottom rail and in tangentially consecutive order as respects each other, the front and rear rings of said lower series being respectively tangent to the front and rear part-ring elements, said lower rings respectively having circumferential slots at the points of tangency with the lower rail and the part-ring elements

and said lower rail and part-ring elements respectively having apertures in register with the respective slots at the respective points of tangency; and a plurality of fastener means releasably received respectively by said last-mentioned slots and apertures for selective release and securement along with the previously mentioned fasteners to respectively accommodate and fix adjustment of the rails and posts.

7. The invention defined in claim 6, in which: the rings and upper and lower part-ring elements are of equal radius; the rings in the lower series are directly below the rings in the upper series; and certain of the upper rings are rigidly connected to certain of the lower rings.

8. In a railing of the class described, the combination of: a post member and a rail member arranged to form a corner; a corner-connecting element within the corner and secured to one member and having an outer arcuate surface the section of a cylinder formed about an axis transverse to the length of the rail member, said surface being tangent to the other member and having a circumferential slot therein including the point of tangency; and releasable fastener means in the slot and engaging said other member at said point of tangency, said fastener means being releasable for circumferential sliding in the slot to enable adjustment of the members relative to each other about the aforesaid axis and said fastener means being securable to fix the members against relative movement.

9. A railing assembly, comprising: a pair of parallel post members; a rail member extending between and forming with the post members a pair of spaced corners; a pair of corner elements respectively within the corners and interconnecting the rail member with the post members, each element being secured to one member and having an arcuate outer surface the section of a cylinder formed on an axis transverse to the length of the rail, said surface being tangent to the other member at the respective corner, and each element having in its arcuate surface a circumferential slot extending to at least one side of the point of tangency of said surface with said other member; and a pair of releasable fasteners, one in each slot and through said other corner-forming member, each fastener being releasable for circumferential sliding in its slot to enable changes in the angle of its corner and being securable to fix a selected corner angle.

10. A railing assembly, comprising: a pair of parallel post members; upper and lower parallel rail members extending between and forming respectively with the post members a pair of upper and a pair of lower corners; a pair of upper and a pair of lower corner brace elements disposed respectively within the corners, each element being secured to one member and having an arcuate outer surface the section of a cylinder formed about an axis transverse to the length of the rail, said surface being tangent to the other of the members at the respective corner and each element having in its arcuate surface a circumferential slot extending to at least one side of the point of tangency of said surface with said other members; and a plurality of releasable fasteners, one in each slot and engaging the tangent portion of the respective member, each fastener being releasable for circumferential sliding in its slot to enable changes in the angle of its corner and being securable to fix a selected corner angle.

11. The invention defined in claim 10, including: an upper series of intermediate elements, each element having an arcuate outer surface the section of a cylinder formed on an axis transverse to the length of the rail and said elements being arranged along the upper rail with said surfaces tangent to said rail and in tangential consecutive order as respects each other, the surfaces of the end elements in said series being respectively tangent to the corner brace elements in the upper corners and each intermediate element having in its surface a first circumferential slot portion including the point of tan-

gency with the upper rail member and each intermediate element having in its surface a second circumferential slot portion including the point of tangency with the next element in said series, each end element in said series having in its surface a circumferential slot including the point of tangency with the respective upper corner brace element; and a plurality of releasable fasteners, one passed through each first slot portion and engaging the tangent portion of the upper rail, one passed through each second slot portion and engaging the next element in said series, and one passed through the end element slot and engaging the respective corner element, each fastener being releasable for circumferential sliding in its respective slot to accommodate corner angle adjustment and being securable to fix said adjustment.

12. In a railing of the class described, the combination of: a post member and a rail member arranged to form a corner; a corner-connecting element within the corner and secured to one member and having an outer arcuate surface the section of a cylinder formed about an axis transverse to the length of the rail member, said surface being tangent to the other member and releasable fastener means normally interconnecting said other member and the corner-connecting element at said point of tangency, said element being releasable to slide around said arcuate surface to enable adjustment of the members relative to each other about the aforesaid axis and said fastener means being securable to fix the members against relative movement.

13. A post for a railing of the class described, comprising: an elongate upright member having a terminal upper end and front and rear upright faces and opposite side faces; a connecting element rigid on the member at the upper end thereof, said member including an arcuate outer mounting surface projecting at the front face of said member and formed about a horizontal axis.

14. The invention defined in claim 13, including: a second connecting element at approximately the level of the first-mentioned element and projecting from one of said side faces, said second element including an arcuate outer mounting surface formed about a horizontal axis normal to the first-mentioned axis.

15. A post for a railing of the class described, comprising: an elongate upright member having a terminal upper end and front and rear upright faces and opposite side faces; a C-shaped connecting element arranged with its open side down to embrace the upper end of the member from above, the axis of said element passing horizontally through the member between said front and rear faces, the free ends of the element being rigidly secured respectively to said front and rear faces and the closed side of said element curving upwardly ahead of, rearwardly over and downwardly behind the upper end of said member.
16. A post for a railing of the class described, comprising: an elongate upright member having a terminal upper end and front and rear upright faces and opposite side faces; a C-shaped connecting element arranged with its open side down to embrace the upper end of the member from above, the axis of said element passing horizontally through the member between said front and rear faces, the free ends of the element being rigidly secured respectively to said front and rear faces and the closed side of said element curving upwardly and forwardly spaced ahead of, rearwardly over and spaced above and downwardly behind and spaced rearwardly from the upper end of said member.
17. The invention defined in claim 16, in which: the member is tubular and has front and rear walls, and one of said walls is extended upwardly and rigidly secured to that portion of the element over the upper end of said member.
